(57) **CLAIM**

The ornamental design for a patient table, as shown and described.

DESCRIPTION

FIG. 1 is a front view of a patient table showing our new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view taken generally from the upper, front, left-hand side thereof;

FIG. 8 is a perspective view taken generally from the upper, front, right-hand side thereof;

FIG. 9 is a perspective view taken generally from the upper, front, left-hand side thereof showing the table surface of the patient table in an alternative lateral position;

FIG. 10 is an enlarged view of the patient table as shown in FIG. 5;

FIG. 11 is an enlarged view of the patient table as shown in FIG. 6; and,

FIG. 12 is an enlarged view of area 12 circumscribed within FIG. 8.

The alternating long-short dashed broken lines depict the boundary of the enlarged view that form no part of the claimed design.

The other broken lines depict portions of the patient table that form no part of the claimed design.

1 Claim, 12 Drawing Sheets
